DESCRIPTION

FIG. 1 is an isometric view of a robotic arm in accordance with the present disclosure;

FIG. 2 is a close-up view of a portion of the robotic arm of FIG. 1 as seen in FIG. 1;

FIG. 3 is a right-side view of the robotic arm of FIG. 1;

FIG. 4 is a close-up view of a portion of the robotic arm of FIG. 1 as seen in FIG. 3;

FIG. 5 is a left-side view of the robotic arm of FIG. 1;

FIG. 6 is a close-up view of a portion of the robotic arm of FIG. 1 as seen in FIG. 5;

FIG. 7 is a top view of the robotic arm of FIG. 1;

FIG. 8 is a bottom view of the robotic arm of FIG. 1;

FIG. 9 is a front view of the robotic arm of FIG. 1;

FIG. 10 is a close-up view of a portion of the robotic arm of FIG. 1 as seen in FIG. 9;

FIG. 11 is a rear view of the robotic arm of FIG. 1; and,
FIG. 12 is a close-up view of a portion of the robotic arm of FIG. 1 as seen in FIG. 11.

The broken line portions are included to show environmental unclaimed subject matter only and form no part of the claimed design.
